UNITED STATES PATENT OFFICE

ERNEST H. PEABODY AND DAVID J. IRISH, OF NEW YORK, N. Y., ASSIGNEES TO THE
BABCOCK & WILCOX COMPANY, OF BAYONNE, NEW JERSEY, A CORPORATION OF
NEW JERSEY.

APPARATUS FOR BURNING FINELY-DIVIDED FUEL.

1,129,309.

Specification of Letters Patent. Patented Feb. 23, 1915.

Application filed September 22, 1911. Serial No. 650,856.

To all whom it may concern:

Be it known that we, ERNEST H. PEABODY and DAVID J. IRISH, citizens of the United States, residing at New York city, borough 5 of Manhattan, county of New York, and State of New York, and New York city, borough of Richmond, county of Richmond, and State of New York, respectively, have invented certain new and useful Improvements 10 in Apparatus for Burning Finely-Divided Fuel, of which the following is a specification.

In certain situations steam boiler furnaces are equipped with the regular grate bars for 15 firing with coal, and with means for firing with finely-divided fuel, such as oil, in combination therewith. Ordinarily these furnaces may be fired with coal. Should, however, the necessity for increasing steam capacity 20 arise, the oil-burning apparatus is put into operation. Usually there is a dead space between the fire doors made up of a cast iron air-cooled casing or of brick-work. This dead space may be utilized for locating 25 the oil burners: that is, the burners may be inserted through the casing or brick-work, the tip of the burners projecting into the furnace. In this event there is no provision for protecting the burners from the heat of 30 the furnace when not in service except by admitting a large excess of air about the burners with consequent deleterious effects on the efficiency, or by disconnecting the burners entirely and removing them from 35 the boiler. If this is not done when firing with coal alone, the oil-burning apparatus is subjected to the furnace heat and is liable to be deteriorated thereby. Moreover, the oil standing in the burner becomes carbonized 40 and the usefulness of the burner thereby destroyed, such burner requiring cleaning before it can be again used.

The object of the present invention is to provide an adequate protection for the burners in boiler furnaces which are equipped for combined coal and oil firing, making them 45 instantaneously available for use when needed. While we have shown in our drawings this arrangement as used in conjunction with 50 a furnace in which coal is burned in combination with oil, the invention is not restricted to such particular use, but is adapted for use in furnaces wherein oil only is used as fuel. In this case it frequently happens that

a portion of the burners may be in use and 55 it becomes necessary to protect from the radiant heat of the furnace those burners which are not in use.

Our invention, therefore, relates to furnaces burning oil only as well as those in 60 combination with coal.

The invention will be understood by reference to the accompanying drawings in which—

Figure 1 is a front view of a furnace for 65 burning coal and oil in combination; Fig. 2 a vertical section on the plane of the line 2—2 of Fig. 1; Fig. 3 a horizontal section on the plane of the line 3—3 of Fig. 1; Fig. 4 an enlarged vertical section on the plane of 70 the line 4—4 of Fig. 3; and Fig. 5 a front view of the burner protecting plate.

Similar reference numerals indicate similar parts in the several views.

Referring to the drawings, the numerals 75 1 and 2 designate the usual coal firing doors of a boiler furnace. Between these doors is placed a cast iron furnace front casing 3 which we have modified for the protection of the oil burner in the following manner: as 80 shown in Figs. 2 and 4, the supply pipe 4, to which the burner 5 is attached is led through a suitable opening in the front wall of the casing, the burner 5 terminating within the casing space. In connection with the 85 burner an air deflecting plate 6 is preferably used consisting of a plurality of blades set at an angle to the plane of their support and designed to deflect the air for combustion from its normal direction of travel, and to 90 impart to it a whirling or rotating motion.

To provide for the adequate protection of the burner and to obviate, therefore, the necessity of removing it to prevent deterioration when the furnace is fired with coal 95 alone, we place in the opening on the furnace side of the burner a refractory block or substantial casting 7, the openings 8 being provided therein to permit of the circulation of air therethrough from the outside 100 to keep the casting cool when the burner is not in operation. To retain the casting 7 in position it is formed with an offset 9 adapted to engage a recess in the casing, as indicated in full lines in Fig. 4. When it is 105 desired to fire with oil, the casting 7 is readily removed from its position by hand. By lifting the casting from its retaining

2
notch, it may be slid down, as indicated in Fig. 2, and by dotted lines in Fig. 4. When firing by coal alone, the casting is raised to its full line position, thus protecting the burner from the furnace heat. A door 10 is pivotally hung or hinged in the front wall of the casing to provide for the admission of air for combustion to the burner. In Fig. 4 the door is shown open.

10 Heretofore, so far as we are aware, the oil pipe has been run straight through the casing into the furnace, and we are the first to locate the burner within the casing space and to provide means which do away with 15 the necessity of the removal of the burner when firing with coal alone to prevent the destruction or deterioration of the burner. The removal of the burner has heretofore involved considerable labor and possible 20 loss of time and loss of use of the burner at a time when its use may be very essential.

It is obvious that the protecting block or casting may be supported in other ways than that shown, and that such expedient 25 may be used in furnaces wherein oil only is used as a fuel.

What we claim and desire to secure by Letters Patent of the United States is:—

1. A furnace casing having an opening, a 30 burner for finely divided fuel terminating within the interior of said casing, and a refractory block or casting adapted to be sup-

ported within the casing when the burner is in use, said casing having a seat to receive said block when placed into said opening in 35 front of the burner.

2. A furnace casing having an opening, a burner for finely divided fuel terminating within the interior of said casing, and a removable refractory block or casting adapted to be set into said opening in front of the burner, said block or casting having an offset to engage a recess in the casing when the former is placed in position to protect 40 the burner.

3. A furnace casing having an opening, a burner for finely divided fuel terminating within the interior of said casing, a refractory block or casting adapted to be supported within the casing when the burner is in 45 use, said casing having a seat to receive said block or casting when raised into said opening in front of the burner, and a door in the front wall of said casing to provide for the admission of air for combustion.

50 In testimony whereof we have hereunto signed our names in the presence of two 55 subscribing witnesses.

ERNEST H. PEABODY,
DAVID J. IRISH.
